BASE FOR A PORTABLE MICROPHONE OR THE LIKE

Maurice M. Palo, Conneaut, Ohio

Application October 23, 1952, Serial No. 21,963

Term of patent 7 years

(Cl. D26—14)

To all whom it may concern:

Be it known that I, Maurice M. Palo, a citizen of the United States, residing at Conneaut, in the county of Ashtabula and State of Ohio, have invented a new, original, and ornamental Design for a Base for a Portable Microphone or the like, of which the following is a specification, reference being had to the accompanying drawing, forming part hereof.

In the drawing:

Figures 2, 3 and 4 are top, side and end views, respectively, of the base of Figure 1.

The dotted line showing of a microphone in Figure 1 is for illustrative purposes only.

I claim:

The ornamental design for a base for a portable microphone or the like, as shown and described.

MAURICE M. PALO.
